UNITED STATES PATENT OFFICE

MAURICE M. GOLDBERG, OF NEW YORK, N. Y., ASSIGNOR TO ANIMATED BOOK MATCH CORPORATION, OF NEW YORK, N. Y., A CORPORATION OF DELAWARE

TOY BOX WAGON

Application filed July 23, 1929. Serial No. 380,428.

This invention relates to toys and more particularly to a toy made of a single sheet of material such as cardboard and foldable to represent various objects such as a wagon, 5 car, circus cage, or the like.

An object of the invention is to so cut and fold a single sheet of material that it may represent objects such as specified above and may also represent a means whereby such 10 object is moved, as, for instance, by some sort of draft animal at the front end.

A further object of the invention is to provide some movable part such as a top or cover, movable to and fro, and a figure so related to 15 such top or cover that it too moves back and forth as the cover is moved.

Details of the construction and mode of slitting and folding the sheet will be understood by reference to the accompanying drawings 20 which show one form of the invention and which, for illustrative purposes, represent a circus wagon.

Figure 1 is a side elevation of such a wagon; 25 Figure 2 represents a top plan view;

Figure 3 a section on line 3—3 of Figure 2;

Figure 4 a section on line 4—4 of Figure 2;

Figure 5 a top view with the cover thrown back;

Figure 6 a side elevation with the parts in 30 the position shown in Figure 5;

Figure 7 is a front elevation;

Figure 8 is an elevation of the rear right hand side portion showing the connection of the cover with the tongue which interlocks 35 with the side portion to hold the sections together;

Figure 9 is a bottom view showing the interlocking portions of the bottom sections; and

Figure 10 is a view of the blank from which the toy is made, said figure showing in dotted lines the position of the folds and in double lines the position of the slits and manner of slitting to form the various sections.

The manner of constructing the device may be best understood by reference to Figure 10 which shows the blank properly shaped and upon which the various sections are indicated. These sections consist of a left side section 1, 45 a right side section 2, a front section 3, back

section 4 and bottom sections A, B, C and D. The particular toy represents a circus wagon so that the side section 1 has some drawings on it of animals which may be colored as desired, the right section 2 indicating an animal in a cage. 55

In order to form the wheels the bottom sections B and D are semi-circularly cut at the points marked 5 so that when the sections B and D are folded under along the dotted lines 60 indicated at 6, the prolongations of the sides which are to represent wheels will remain in the plane of the sides.

In Figure 1 the wagon is shown as being drawn by a figure somewhat representing a 65 goose, and this effect is produced by a portion 7 of the blank, which is a prolongation of the right side section, the figure being indicated at 8. When the blank is folded the part 8 is passed through the slit 9 in the front 70 section 3. A part 10 projecting below the plane of the bottom sections when folded and on a level with the wheels serves as a support for the figure representing the draft animal and also as a means to lock the parts together. 75

The method of folding the blank is indicated by the arrows which are adjacent the dotted lines in Figure 10. Where these arrows have their butt ends adjacent the dotted line, the fold is made backward or away from 80 the plane of the drawing. Where the arrow has its end or point adjacent the line of fold, it indicates that the fold is upward. For instance, along the dotted line 6 the two bottom sections are folded under. The same is true 85 of the fold along the dotted lines 11.

After the sections A, B, C and D are folded under and a fold has been made at dotted lines 12, 13, 14, 15, 16, 17, 19 and 20 as indicated by the arrows, the part 8 is passed 90 through the slot 9. Sections A and C are folded first, then sections B and D folded under them and the tongue 21 of section B passed through the slots 22 of section D, as indicated in Figure 9.

In order to form a top or cover, the left side 1 is continued but is cut at 23 along the edge where it joins the side section, leaving a portion integral with the side section which forms a tongue 24. The tongue 24 is bent back 100

at 17 but at 19 the top section is bent up and the cover pivots about the dotted line 19 which acts as a hinge. The top may be bent again along the line 20 to form a display back 5 32. Projecting from the tongue in a direction opposite to the top section is an integral portion 25 which may likewise have integral with it a figure 26. The part 25 is bent upwardly at 27, indicated by the end of the arrow 10 touching the dotted line, and the figure is passed through a slot 28 in the top section. Since the top section pivots about the line 19 and since the portion 25 carrying the figure pivots about the point 27, there will be 15 a relative movement between the figure and the top when the top is moved between open and closed positions. In order that the structure may be properly held together the tongue 24 is provided with a part 29 which interlocks 20 with slits 30 in the right side section, this being also clearly shown in Figure 8.

To simulate a driver an integral portion of the front section 3 is bent back at 16 and shaped as shown at 31. It is to be noted that 25 the blank when folded as indicated has the appearance of Figure 1 when the top is closed. When open, the figure 31 may occupy an upright position as shown in Figure 6. The bent-over portion 32 forming the display back 30 may have depicted upon it some scene appropriate to the figure or object 26, which moves relative to the background as the cover is moved.

Various objects may be formed and different parts thereof may be made to move by applying the principle of my invention as above described, and I therefore do not desire to be limited to the particular details shown.

What is claimed as new is:

40 1. A blank foldable to represent a wagon or the like, said blank having front and rear sections the front section provided with a slit, each said sections adjoining a side section and a bottom section adjoining the side 45 and front and rear sections, a prolongation of one of the side sections being formed to represent a figure and means integral therewith to project through and interlock with the slit in the center of the front section when 50 the sections are folded so that said figure simulates a draft animal for the wagon.

2. A blank foldable to represent a toy wagon or the like and comprising end sections, each end section adjoining a side section, and a bottom section adjoining the end sections and side sections, a top section extending from a side section opposite one of the bottom sections and cut for a substantial portion of its length where it adjoins the side section leaving a tongue integral with the side section, said top provided with a slit and said section being folded at one edge of the tongue to form a hinged top, said tongue having an integral portion at the side opposite 60 from the hinged top supporting a figure, 65

which portion when folded back and the figure passed through a slit in the hinged top will cause a movement of the figure in the slit when the top is moved between closed and open positions.

3. A blank foldable to represent a wagon or the like having end, side and bottom sections, a top section adjoining one of the side sections and having a slit therein and cut for a substantial portion of its length where it adjoins the side section leaving a tongue integral with the side section, said top section being folded at one edge of the tongue to form the hinge for the top, an integral projection extending from the tongue opposite the top and supporting a figure integral therewith, said projection being folded back from the one edge of the tongue and passed through the slit in the top section.

Signed at New York, this 11th day of July, 1929.

MAURICE M. GOLDBERG.
